UNITED STATES PATENT OFFICE.

MARTIN A. KLEIN, OF NEW YORK, N. Y.

DESIGN FOR A PENDANT FOR WEARING APPAREL.

Application filed October 10, 1928. Serial No. 28,421. Term of patent 14 years.

To all whom it may concern:

Be it known that I, MARTIN A. KLEIN, a citizen of the United States, and a resident of the city of New York, borough of The Bronx, in the county of Bronx and State of New York, have invented the new, original, and ornamental Design for Pendant for Wearing Apparel, of which the following is a specification.

Reference is to be had to the accompanying drawing forming a part thereof, in which

I claim:

The ornamental design for a pendant for wearing apparel, as shown.

MARTIN A. KLEIN.
